DELAWARE.

MANIFOLD FOR INTERNAL-COMBUSTION ENGINES.

1,323,378.

Specification of Letters Patent.

Patented Dec. 2, 1919.

Application filed September 29, 1917. Serial No. 194,061.

To all whom it may concern:

Be it known that we, EUGENE C. RICHARD and WALTER G. HEGINBOTTOM, both citizens of the United States of America, both residing at Flint, in the county of Genesee and State of Michigan, have invented certain new and useful Improvements in Manifolds for Internal-Combustion Engines, of which the following is a specification, reference being had therein to the accompanying drawings.

The invention relates to internal combustion engines and has particular reference to a manifold construction by which proper temperature conditions are maintained in the intake. It is a well-known fact that the warming of the intake manifold is advantageous in producing a proper explosive mixture, but, on the other hand, the overheating of this manifold is detrimental. Thus, if the intake manifold is integral with the exhaust manifold or is connected thereto by good heat-conducting means, there is danger of overheating. In the present invention we have arranged the intake and exhaust manifolds in proximity so that heat radiated from the one will be absorbed by the other, and at the same time have secured these manifolds without any direct mechanical connection therebetween which would transfer heat by conduction. Inasmuch as the transfer of heat by radiation is much slower and more uniformly distributed than transfer by conduction, our improved structure has the advantage of imparting just the right degree of heat to the indrawn explosive mixture.

In the drawings:

Figure 1 is a side elevation of the manifold; and Fig. 2 is a vertical cross section through Fig. 1.

A is the intake manifold of a multi-cylinder engine and B is the exhaust manifold thereof. Each of these manifolds is provided with a plurality of inwardly-extending tubes C C', etc., D D', etc., for connecting with the inlet and exhaust passages of the several cylinders.

To provide for the transference of heat by radiation the manifolds A and B are constructed with portions lying parallel to each other but spaced so as to avoid direct mechanical contact and heat conduction. This arrangement is conveniently obtained by ar-

ranging the two manifolds in parallel vertical planes with their adjacent faces machined so that they can be arranged parallel to and normally spaced from each other. Accuracy in spacing is secured by machining the inner ends of the tubes C C' D D' with fixed dimensions between the same and the machined surfaces of the manifold body. Thus when the parts are assembled the two manifolds will lie in close proximity and will nevertheless be out of contact. As shown, the exhaust manifold is arranged in the space between the inlet manifold and the engine cylinders and the machined face E of the exhaust manifold lies parallel and adjacent to the machined face F of the intake manifold. Clamps G may be used for securing the manifolds to the engine cylinders, the ends of said clamps bearing at H and H' upon co-operating bearings of the exhaust manifold and set-screws I arranged centrally of the clamps bear against co-operating bearings on the intake manifold. The clamps themselves are secured by bolts or studs J which extend outward from the cylinder-block intermediate the tubes C and D.

With the construction described the manifolds are easily mounted and taken off and when in position will be uniformly spaced throughout the entire extent of their machined surfaces E and F. Whenever the engine is in operation the heat of the exhaust manifold is radiated to the adjacent face of the inlet manifold and by properly proportioning the extent of surface any desired heating effect may be produced.

What we claim as our invention is:

1. In an internal combustion engine, the combination of intake and exhaust manifolds having surfaces in proximity to each other, and means for securing said manifolds spaced from and out of direct heat-conducting contact with each other, and predeterminedly spaced from each other to provide a predetermined amount of heat radiation from one of said surfaces to the other.

2. In an internal combustion engine, the combination of intake and exhaust manifolds having parallelly-arranged adjacent surfaces, and means for securing said manifolds spaced and out of heat-conducting contact between said surfaces.

3. In an internal combustion engine, the

combination of intake and exhaust manifolds having oppositely-facing machined surfaces, and means for securing said manifolds with said opposite surfaces uniformly spaced and 5 maintained out of heat-conducting contact with each other.

4. In an internal combustion engine, the combination of intake and exhaust manifolds arranged one in the space between the 10 engine and the other and both having adjacent parallel faces, and laterally-extending portions of said manifolds for connecting the same with the respective engine cylinders and also constituting a means for holding 15 said parallel surfaces uniformly spaced and out of heat-conducting contact with each other.

5. In an internal combustion engine, the combination of intake and exhaust manifolds one arranged in the space between the 20 engine and the other and having adjacent flat parallelly-arranged surfaces for the radiation of heat from one to the other, and connections between said manifolds and the 25 respective engine cylinders forming means for securing and uniformly spacing said

parallel surfaces out of heat-conducting contact with each other.

6. In an internal combustion engine, the combination of an exhaust manifold having 30 an outer flat machined face, an intake manifold arranged at the side of the outer face of said exhaust manifold and having an inner flat machined face parallel to the outer face of said exhaust manifold, and tubular 35 connections between said manifolds and the respective engine cylinders dimensioned to space said parallel surfaces and hold the same out of heat-conducting contact with each other. 40

7. In an internal combustion engine the combination with an intake manifold of an exhaust manifold, said manifolds having adjacent machined surfaces spaced from each other a predetermined distance to provide 45 a predetermined amount of heat-radiation from one surface to the other.

In testimony whereof we affix our signatures.

EUGENE C. RICHARD.
WALTER G. HEGINBOTTOM.
